UNITED STATES PATENT OFFICE.

CHARLES ALGERNON PARSONS AND GEORGE GERALD STONEY, OF
NEWCASTLE-UPON-TYNE, ENGLAND.

STEAM-TURBINE.

No. 822,150.

Specification of Letters Patent.

Patented May 29, 1906.

Application filed September 19, 1904. Serial No. 225,114.

To all whom it may concern:

Be it known that we, CHARLES ALGERNON PARSONS and GEORGE GERALD STONEY, both subjects of the King of Great Britain and Ireland, and residing at Heaton Works, Newcastle-upon-Tyne, in the county of Northumberland, England, have invented certain new and useful Improvements in and Relating to Steam-Turbines, of which the following is a specification.

Our invention relates to improvements in the method of blading of elastic-fluid turbines, turbine-pumps, and the like described in Patents Nos. 549,010, 639,608, 655,414, and 15 666,283, and has for its object to facilitate the manufacture of such apparatus and to provide for the holding of the strip-blades more securely and with greater accuracy of position.

Our invention consists in bladed root-strips for steam-turbines formed by, first, the cutting of transverse face-grooves in the metal root-strip; second, the insertion of the blades into these grooves from the face; third, the placing of the strip with its blades 25 in a grooved die adapted to retain the blades and strip in their relative positions; fourth, the application of great lateral pressure, so as to grip the blades in the strip and close up the air-spaces, thus providing a blade-carrying strip ready for attachment in any 30 of the usual ways to the turbine drum or disk.

Our invention further consists in the construction of blade-rings, hereinafter described.

Referring to the accompanying drawings, Figure 1 shows an elevation and a section of one of the forms of blades which may be used, though we do not confine ourselves to this particular form. Fig. 2 shows a plan and elevation of the metal root-strip with curved transverse grooves on its face before pressure has been applied to the root-strip. Fig. 2^a is an end elevation showing the section and relative proportions (approximately) of the width of the blade and root-strip before the application of pressure or hammering. Fig. 3 shows a plan and elevation of the blades inserted in the metal root-strip as 45 they appear after pressure has been applied in the manner illustrated in Fig. 4. Fig. 4 shows a plan and sectional elevation of the grooved die for fixing the blades firmly to the metal strip. Fig. 5 shows the blades at

tached to a drum or casing. Fig. 6 shows a 55 method of attaching the blades to a drum or casing by means of a calking-ring.

In constructing a blade-ring according to our invention the ends of the blades are made of drawn, rolled, or other material, as 60 described in Patent No. 639,608, and may or may not be notched at their roots to give a better holding power. The blades are of a form as shown in Fig. 1 and are inserted into the transverse curved notches *a* of a 65 metal root-strip *b*, Fig. 2. These notches in the metal root-strip are cut in it by an oscillating cutter, as described in Patent No. 549,010, or by a conical cutter which is preferably made thicker at the tips of the teeth 70 than at the roots to give clearance, or they may be made in any other well-known way. The width of the root-strip *c*, Figs. 1 to 2^a, may be greater than that of the blades. The strip, with the blades inserted in it, is then 75 placed in a grooved die *d*, Fig. 4, and is pressed or hammered so as to cause the metal strip to fill up the air-spaces and grip the roots of the blades firmly. Pressure for effecting this may be conveniently applied 80 to a plate *e*, bearing upon the strip. An important advantage of this method of manufacture is that the dies prevent the blades and strip from changing their relative positions while the blades are being secured in 85 the strip. After securing the blades in this manner the bladed strips are removed from the die and inserted into grooves, Fig. 5, dovetailed or otherwise prepared for their reception in the drum or casing and firmly 90 fixed in place by calking the metal *f* in the strip *c*, Fig. 3, which intervenes between the blades. Sometimes a calking-ring *g*, Fig. 6, is inserted in the groove along with the strip, in which case the metal between the blades 95 may or may not be calked.

Having now described our invention, what we claim as new, and desire to secure by Letters Patent, is—

1. As a new article of manufacture, a combined holding-ring with blades therein swaged together into one substantially integral structure.

2. As a new article of manufacture, a combined holding-ring with blades therein swaged together into one substantially integral structure with substantially smooth and parallel sides.

3. As a new article of manufacture, a detached bladed ring for turbines having blades firmly swaged therein.
4. As a new article of manufacture, a bladed strip for turbines and the like having in combination a strip of rectangular section having faced grooves formed therein, blades inserted in said grooves from the face so that the roots lie along the bottom of the grooves and held in said grooves by pressure due to a flow of the metal of the strip to uniformly grip the roots of the blades, the whole bladed strip being then ready for insertion in the turbine-drum without further calking of the strip for the purpose of securing the blades.

5. A bladed strip for turbines having grooves, blades located in the grooves and held in place by the metal between the roots of the blades, which metal is swaged by means of pressure applied transversely of the strip, substantially as described.

In testimony whereof we have signed our names to this specification in the presence of two subscribing witnesses.

CHARLES ALGERNON PARSONS.
GEORGE GERALD STONEY.
